(57) **CLAIM**

The ornamental design for a golf tee holder with built-in attachment for a golf cart, as shown.

DESCRIPTION

FIG. 1 is a front elevational view, showing my new design;

FIG. 2 is a rear elevational view, thereof;

FIG. 3 is a top plan view thereof; the bottom plan view being a mirror image thereof;

FIG. 4 is a left side elevational view thereof;

FIG. 5 is a right side elevational view thereof;

FIG. 6 is a top, front and right side perspective view, shown in use with tees disclosed in broken lines;

FIG. 7 is a top plan view, shown in use with tees and golf cart rail in broken lines;

FIG. 8 is a reduced scale top, front and right side perspective view, shown in use on the driver side of a golf cart in broken lines; and,

FIG. 9 is a reduced in scale bottom, front and left side perspective view, shown in use on the passenger side of a golf cart in broken lines.

The broken line shown on the drawings form no part of the claimed design.

1 Claim, 5 Drawing Sheets
